APPARATUS AND METHOD FOR
COMBINING YARNS

Robert E. McDonald, Waynesboro, Va., assignor
to E. I. du Pont de Nemours and Company,
Wilmington, Del., a corporation of Delaware

Application January 4, 1951, Serial No. 204,374

5 Claims. (Cl. 28—71.5)

1

This invention relates to an apparatus for combining running ends of yarn to form a tow or rope of yarn, and is more particularly concerned with an apparatus for adding an end of yarn to moving yarn without interrupting the movement of the yarn.

In the production of stable fiber, yarns from several creel or spinning positions may be combined into a large bundle, called a tow or rope. The tow is frequently a more convenient form in which to handle the fibers during after-treatments, including that of cutting into short lengths, called staple.

The addition of an end of yarn to moving yarn or tow is relatively easy when the yarns are wet, as the water causes the yarns to adhere. Dry hydrophilic yarns such as acetate yarn, can be combined by sponging in, i. e., the yarns are wetted to cause them to adhere. However, certain of the new synthetic fibers do not wet easily, and it is difficult to add a yarn end to running yarn or tow without interrupting movement of the yarn.

Accordingly it is an object of the present invention to provide an apparatus for adding a yarn end to running yarn or tow; particularly, an apparatus which will be effective regardless of the condition and type of yarn. Other objects of the invention will become apparent from the following description, the accompanying drawing and the claims.

In accordance with the present invention an apparatus is provided which comprises a slotted tube adapted to accommodate running yarn or tow and a yarn end to be added, yarn twisting means, including a tangential air inlet into the tube connected to a suitable source of air or other fluid under pressure, adapted to cause a swirling motion in the tube for twisting the yarn end about the running yarn during passage through the tube, and cutting means located near the outlet of the tube and adapted to trim off excess yarn from the added end of yarn.

An embodiment of the invention will now be described with reference to the drawing, in which,

Fig. 1 is a plan view of the apparatus, and

Fig. 2 is a corresponding front elevation.

The apparatus is positioned so that the completed tow will pass through the center of tube 10 and on to the next operation. A guide 11 is provided to keep the tow centered in the tube. Tube 10 should have an inside diameter sufficiently large to accommodate the tow without actually contacting it, but need not exceed this

2

minimum requirement by a great deal. An inside diameter of 5 to 20 times the diameter of the tow is suitable. The length of the tube should be at least several times the diameter. It may be formed of any suitable material such as metal, glass, or plastic.

The tube is provided with a lengthwise slot 12 of sufficient width so that running yarns may be drawn through the slot to position them in the tube. A tangential air inlet pipe 13 is provided near the inlet end of tube 10 and arranged so that release of a blast of air through the pipe will cause air to swirl around in the tube. The pipe 13 leads to a suitable source of compressed air, the flow being controlled by valve 14.

A running yarn or tow 16 is shown passing through guide 11, tube 10 and on to the next handling means, such as draw rolls, a packaging device or the feeding device of a stable cutter. An end of yarn 18, running or stationary, to be added to yarn or tow 16 is drawn through slot 12 to position it in tube 10. The end of yarn leaving the outlet end of the tube is pulled to one side and held moderately taut. If yarn 18 is a running end, it must be pulled away from the tube at a rate sufficient to keep it taut. While this can be done manually, a more convenient method is to provide an automatic collecting device. A simple and effective device is a suction tube, the end of which is indicated at 19, which will suck the yarn end away to a suitable receptacle. The operation of this device is similar to that of a vacuum cleaner.

A cutting blade 20 is arranged near the outlet of tube 10 in position to cut off yarn end 18 when the yarn is drawn against the blade. This may be a razor blade supported in holder 21. The tube 10, guide 11 and holder 21 are held in position by any convenient means, such as being bolted to a base 22. Supports 24 and 25 are shown for holding the tube 10 at the proper distance above the base 22.

With the apparatus positioned as shown with the yarn running through it, valve 14 is opened to release a blast of air into tube 10. The blast of air causes the air in tube 10 to swirl around and twist yarn end 18 tightly about running yarn or tow 16. Thereupon yarn end 18 is drawn against blade 20 by the movement of yarn or tow 16 and is trimmed off close to the running yarn. Valve 14 is closed and the apparatus is ready for the addition of another end of yarn to the running yarn or tow 16. The whole operation has taken only a few seconds and is simple and easy to perform with any type of yarn.

The apparatus described may be permanently mounted on other equipment in position for use when required. On the other hand, the apparatus can be made portable, by mounting on a suitable base. An operator then carries it around with him and plugs into an air hose at a station located where the apparatus is to be used. The apparatus can be used to add an end of yarn directly to the main tow or rope. However, the preferred method is to secure the yarn end to a strand of yarn of not much over 4000 to 6000 denier and then guide the strand of yarn into the main tow or rope. With this procedure the main rope does not pass through the tube.

While the invention has been described in terms of a preferred embodiment thereof, it is apparent that many different embodiments may be made without departing from the spirit and scope of the invention, and it is to be understood that the invention is not limited by the specific illustration except to the extent defined in the following claims.

What is claimed is:

1. An apparatus for adding a yarn end to running yarn which comprises a tube having a diameter sufficient to accommodate running yarn and a yarn end to be added, said tube being provided with a lengthwise slot for introducing a yarn end, and means including a tangential air inlet for blowing air into said tube, the axis of said inlet intersecting a diameter of said tube at a point sufficiently distant from the axis of the tube to impart a swirling motion to the air in said tube.

2. An apparatus for adding a yarn end to running yarn which comprises a tube having a diameter sufficient to accommodate running yarn and a yarn end to be added, said tube having a length at least several times the diameter, said tube being provided with a lengthwise slot for introducing a yarn end, means including a tangential air inlet for blowing air into said tube, the axis of said inlet intersecting a diameter of said tube at a point sufficiently distant from the axis of the tube to cause a swirling motion in

5

said tube sufficient to twist a yarn end about the running yarn, and cutting means located adjacent to the outlet end of said tube in position to trim off excess yarn from an added end of yarn as the yarn leaves said tube.

3. An apparatus for adding a yarn end to running yarn which comprises a tube adapted to accommodate running yarn and a yarn end to be added, said tube being provided with a lengthwise slot for introducing the yarn end, a cutting edge located adjacent to and directed toward the outlet end of said tube, and means including a tangential air inlet for blowing air into said tube with a swirling motion adapted to cause the yarn end to be twisted about the running yarn and be drawn against said cutting edge to trim off excess yarn from the yarn end.

4. A method for adding a yarn end to running yarn which comprises the steps of passing the running yarn and the yarn end together through a restricted passageway, thereafter guiding the yarn end away from the running yarn and in front of a cutting edge, and then blowing air into the passageway with a swirling motion to cause the yarn end to be twisted about the running yarn and be drawn against the cutting edge to trim off excess yarn from the yarn end.

5. A method for adding a yarn end to running yarn which comprises the steps of guiding the yarn end to be added in closely parallel relationship to the running yarn, thereafter guiding the yarn end away from the running yarn and in front of a cutting edge, and then blowing air with a swirling motion around the parallel yarns to cause the yarns to be twisted together and the added yarn to be drawn against the cutting edge to trim off excess yarn from the yarn end.

ROBERT E. McDONALD.
